UNITED STATES PATENT OFFICE

154,624

DESIGN FOR A GAS PRESSURE REGULATOR
OR SIMILAR ARTICLE

Fritz Niesemann, Pittsburgh, and Harold Van Doren, Ardmore, Pa., assignors to Rockwell Manufacturing Company, Pittsburgh, Pa., a corporation of Pennsylvania

Application February 21, 1947, Serial No. 137,091

Term of patent 14 years

(Cl. D78—1)

To all whom it may concern:

Be it known that Fritz Niesemann, a citizen of the United States and resident of Pittsburgh, in the county of Allegheny and State of Pennsylvania, and Harold Van Doren, a citizen of the United States and resident of Ardmore, in the county of Montgomery and State of Pennsylvania, have invented a new, original, and ornamental Design for a Gas Pressure Regulator or Similar Article, of which the following is a specification, reference being had to the accompanying drawing, forming a part thereof, wherein:

Figure 1 is a perspective view of a gas pressure regulator or similar article, showing our new design;

Figure 2 is a top plan view thereof;

Figure 3 is a bottom plan view; and

Figure 4 is a side elevation.

We claim:

The ornamental design for a gas pressure regulator or similar article, as shown.

FRITZ NIESEMANN.
HAROLD VAN DOREN.
